HINGED SKIRT AND TROUSER HANGER

Dwight C. Brown, 5712 N. 20th St.,
Arlington, Va. 22205

Filed Mar. 1, 1974, Ser. No. 447,301

Term of patent 14 years

Int. Cl. D6—08

U.S. Cl. D6—252

FIG. 1

FIG. 2

FIG. 3

FIG. 4

FIG. 5

FIG. 1 is a top plan view of a hinged skirt and trouser hanger, in partially opened position.

FIG. 2 is an elevation of one side of the hanger shown in FIG. 1.

FIG. 3 is an end view taken from the left of FIG. 2.

FIG. 4 is a side elevation opposite that shown in FIG. 2.

FIG. 5 is a bottom plan view of the hanger shown in FIG. 1.

I claim:

The ornamental design for a hinged skirt and trouser hanger, as shown and described.
